UNITED STATES PATENT OFFICE.

CHAUNCEY FRANK STILLMAN, OF NORTH BERGEN, NEW JERSEY.

BUFFER FOR AMUSEMENT CARS.

1,420,065.

Specification of Letters Patent. Patented June 20, 1922.

Application filed June 15, 1921. Serial No. 477,679.

To all whom it may concern:

Be it known that I, CHAUNCEY FRANK STILLMAN, a citizen of the United States, and a resident of North Bergen, in the 5 county of Hudson and State of New Jersey, have invented a new and Improved Buffer for Amusement Cars, of which the following is a description.

This invention relates to amusement apparatus and has particular relation to a buffer construction designed for use in connection with a passenger-carrying car adapted to travel in any direction on a suitable platform.

In the common construction of buffers for this purpose, it has been the general practice to employ an annulus which is maintained in concentrically spaced relation to the body of the car by means of compression springs radially disposed between the body and the annulus in order to absorb the shocks incident to the contact of said cars with each other and with the sides or guard rails of the platform.

The present invention contemplates the employment of tension springs respectively connected at their opposite ends to the annulus in a car body which are normally maintained under tension to maintain the annulus in concentric spaced relation in order to cause the car body to continue in the same direction of travel when contact is made, whereby to bring the same to a gradual stop for minimizing the shock.

Another object and advantage of the present invention resides in the provision and arrangement of tension springs for the purpose set forth which operate to support and maintain the annulus or buffer ring in a predetermined and positive horizontal plane or a plane parallel to the bottom of the car body.

With the above recited and other objects in view, the invention resides in the novel construction, combination and arrangement of parts as set forth in the following specification, pointed out in the appended claims, and illustrated in the accompanying drawings, it being understood that the right is reserved to embodiments other than those actually illustrated therein to the full extent indicated by the general meaning of the terms in which the claims are expressed, and by variations in the phraseology of the same.

In the drawings—

Figure 1 is a side elevation of an amuse-

ment car equipped with a buffer constructed in accordance with the invention, parts being broken away and shown in section to illustrate the underlying structure; 60

Figure 2 is a plan view thereof;

Figure 3 is an enlarged detail horizontal sectional view illustrating the manner in which the springs are secured to the car body. 65

Referring to the drawings by characters of reference, 10 designates a car, preferably of circular construction, which is mounted on the usual caster wheels 11 and is provided with the interior seating arrangement 12 for 70 the accommodation of passengers. The buffer construction which constitutes the feature of the present invention includes an annulus 13 preferably constructed from angle iron with the upper and lower flanges 14 75 and 15 disposed inwardly. A plurality of superposed rows of coiled tension springs 16 are secured at their opposite extremities to the annulus and the body of the car. The upper row of springs are connected to the 80 upper flange 14 and are inclined upwardly from their outer end to the inner ends while the lower row of springs are connected at their outer ends to the lower flange 15 and are inclined downwardly from their outer 85 ends to the inner ends which are connected to the car body. By this arrangement an inclination of the springs which are under tension, it will be appreciated that the annulus is normally maintained in concentrically spaced relation with respect to the car body and the opposite inclination of the upper and lower rows of springs function to normally hold the annulus in a predetermined plane relative to the plane of the bottom of the car without employing additional supporting means. 90 95

As illustrated, the opposite extremities of the springs are bent to form attaching eyes 17 which receive the U-bolts 18 which are 100 designed to be passed through the car body or the flanges of the annulus and receive the retaining nuts 19.

In use and operation of the buffer, when the annulus contacts with an object, the 105 springs on the opposite side of the car with respect to the point of contact will be placed under a greater tension due to the relative movement of the car body with respect to the annulus by reason of the momentum of 110 the car body. By this arrangement the shock incident to the contact of the annulus with

an object is minimized and greatly reduced in comparison to the reverse action set up by the employment of compression springs.

I claim:

- 5 1. A buffer construction for amusement cars of the character set forth, comprising a rigid annular band and radially disposed tension springs connecting the band to the car body for holding the same in encircling
- 10 relation with respect thereto, whereby the shocks incident to the contact of the car with another or with the sides of a platform will be absorbed by the tension springs at the opposite side of the car to that with
- 15 which the contact is made.
2. A buffer construction for amusement cars of the character set forth, comprising a rigid annular band and radially disposed tension springs connecting the band to the
- 20 car body for holding the same in encircling

relation with respect thereto, whereby the shocks incident to the contact of the car with another or with the sides of a platform will be absorbed by the tension springs at the opposite side of the car to that with which the contact is made, whereby the car body will continue in the same direction of travel and will be gradually arrested in its movement. 25

3. A buffer for amusement cars of the character set forth, comprising a rigid annulus, and superposed rows of tension springs connected at their outer ends to the annulus and at their inner ends to the car body, the upper row of springs being inclined upwardly from the outer to the inner ends and the lower row being inclined downwardly from the outer to the inner ends. 30 35

CHAUNCEY FRANK STILLMAN.
